FUEL INJECTION PUMP

John Dickson, Huntington Woods, and Kenneth L. Hulsing, Plymouth, Mich., assignors to General Motors Corporation, Detroit, Mich., a corporation of Delaware

Application March 17, 1948, Serial No. 15,458

14 Claims. (Cl. 103—41)

1

This invention generally relates to fuel injectors and more particularly to improvements in fuel injection pumps for internal combustion engines.

The principal object of this invention is to provide in a fuel injection pump relatively movable pump plunger and sleeve members forming a fuel compression space therebetween, each having few cooperating fuel passages, ports and control edges of simple form to vary the pressure and volume of the fuel in this space during the fuel filling, fuel compression and pressure discharge strokes and providing on the discharge stroke, by-pass from, trapping and compression of the fuel in and controlled start and end of discharge of the compressed fuel from the fuel compression space so that controlled quantities of fuel are discharged therefrom and injected in an internal combustion engine at more uniform pressure, velocity and spray pattern over the range of relative velocity of movement between the plunger and sleeve members.

The combined means by which this object is accomplished will become apparent by reference to the following detailed description and drawings of two different modifications of fuel injection pump mechanisms incorporating features for providing improved fuel injection characteristics for internal combustion engines.

Figure 1 of the drawing is a longitudinal sectional view of one form of fuel injection pump of the fluid pressure operated type.

Figure 2 is a transverse sectional view taken on line 2—2 of Figure 1.

Figure 3 is a longitudinal sectional view of another form of fuel injection pump of the mechanically operated type.

As best illustrated in Figure 1 the fluid pressure operated fuel injection pump comprises a pump body 1 having an axial bore 3 provided with larger diameter counterbores 5—6 at opposite ends. The pump body is shown inserted in fluid tight relation in a fuel pressure supply cavity 7 in a cylinder head 9 of an internal combustion engine, by means of gaskets 10—11 between the body and engine cylinder head so that the body counterbore 5 opens into the engine combustion chamber adjacent the inner surface of the cylinder head.

A hollow cylindrical sleeve 13 having an external packing ring 14 is reciprocal in the body bore 3 and is provided with an external flange 15 shown in sliding contact with a smaller diameter inner end portion 17 of the counterbore 6. A flanged annular closure member 21 having a gasket 23 thereon is seated on an internal

2

flange in the body counterbore 6 and a packing ring 25 is provided in an internal annular groove in the closure member so that the packing ring is in sliding contact with the external surface of the reciprocal sleeve 13. A clamping head 27 is seated on the outer faces of the body 1 and closure member 21 to clamp the closure member in fluid tight relation with the body and sleeve and to retain the body in fluid tight relation in the cavity 7 of the engine cylinder head 9. Suitable injection pump hold-down means, generally indicated at 28, are provided on the engine cylinder head 9 to engage the clamping head 27 of the injection pump for clamping it in place as shown.

A plunger 30 having a smaller diameter outer end portion 31 is rotatably mounted in an opening in the clamping head 27 coaxial with the bore in the reciprocal sleeve 13 into which the inner smaller diameter end of the plunger 30 projects. A lever 33 is secured to the outer end 31 of the rotatable plunger 30 for adjusting it angularly with respect to the head 27 and bore of the sleeve 13 and to prevent reciprocal movement thereof of the plunger 30. A stack of dished spring washers 35 or suitable helical spring means and a thrust collar 37 are placed around the outer end of the rotatable plunger 30 and within a cavity 39 in the clamping head 27. The thrust collar 37 is positioned between the outer end of the head cavity 39 and the stack of spring washers 35 and the other end of the stack of washers contacts the outer end of the reciprocal sleeve 13 and urges it inwardly of the body bore 3 and the exterior flange 15 on the plunger 30 is accordingly urged inwardly and slides in the reduced diameter portion 17 of the outer end body counterbore 6.

The inner end of the reciprocal sleeve 13 is closed by a check valve seat member 41 which is seated thereon by a fuel discharge nozzle 42 which is clamped thereto by an actuating piston 45 threaded on the outer end of the sleeve 13. The piston 45 is provided with a longitudinal opening coaxial with the body bore 3 and is provided with an internal flange in clamping engagement with a flange on the nozzle 42 which has a tip portion projecting out of the piston opening and into the engine combustion chamber. The piston 45 is provided with external packing rings 47 slidable into the inner end counterbore 6 of the body 1 when the compression pressure in the engine compression chamber exerts sufficient force on the piston to overcome the force exerted by the spring washers 35 acting on the other end of the reciprocal

sleeve 13. The piston 45 and sleeve 13 reciprocal thereby is prevented from rotating in the body 1 by a pin 49 threaded in the body 1 and extending into a longitudinal extending external slot 41 in the sleeve 13, as best shown in Figure 2.

The space in the outer end of the bore of the reciprocal sleeve 13 between the inner end face of the reduced diameter portion 28 of the rotatable plunger 30 and the check valve seat 41, generally indicated at 53, serves as a fuel pumping chamber. The wall of this chamber is formed by longitudinally spaced internal grooves 55-57 in the sleeve bore forming a land 59 therebetween of the same diameter as the plunger bore.

The pump body 1 is provided with a radial fuel inlet passage 61 extending from the fuel pressure supply cavity 1 to the body bore 3. The outer end of the fuel inlet passage is enlarged at 63 and a fuel inlet filter element 65 is located therein. The reciprocal sleeve 13 has a flat 67 formed thereon which is in continuous registration with the fuel inlet body passage 61 for all relative positions of the plunger with respect thereto. A drilled passage in the reciprocal sleeve 13, serving as a combined fuel inlet and by-pass port 69, extends radially from the flat 67 on the sleeve 13 to the interior of the bore therein and another passage spaced longitudinally outwardly from the port 69 and extending diametrically from the flat part way through the sleeve 13 forms a fuel inlet and relief port 71 and a fuel discharge port 72 diametrically opposite the port 71. The rotatable plunger 29 is provided with a combined fuel inlet, by-pass and relief groove 73 of semi-annular form normally registering with the fuel inlet and by-pass port 69. Radial and axial passages 75-77 in the rotatable plunger 29 lead from the plunger groove 73 to the inner end face thereof and therefore to the pumping chamber 51 to permit fuel under pressure to enter and fill this chamber and these plunger passages. The rotatable plunger 29 is also provided with a helical fuel discharge groove 78 normally registering with the inlet and relief port 71 to permit fuel under pressure to also fill this plunger groove. A longitudinal fuel discharge passage 79 extends from the discharge port 72 in the reciprocal sleeve 13 to registering annular grooves 81 formed in the engaging faces of the sleeve 13 and check valve seat 41, from which a discharge passage 83 extends to the center of the outer face of the valve seat. An axial discharge passage 85 is formed in the nozzle 43 having a counterbore 86 adjacent the inner end face and containing a check valve disk 87 provided with peripheral grooves for establishing communication between the discharge passage of the nozzle and the discharge opening 83 in the seat 41 when the disk 87 is spaced from the seat 41. Fuel spray discharge openings 89 extend radially and axially outwardly from the nozzle passage 85 through the tip of the nozzle which projects through the piston 45 and into the engine combustion chamber.

With the pump sleeve 13 and plunger 29 in the normal position, as shown at the end of the fuel filling stroke with the fuel inlet passages, ports, grooves and pumping chamber filled with fuel under pressure from the fuel pressure supply cavity 1 in the engine cylinder head as described above, the following events occur upon inward movement of the piston 45 and sleeve 13 on the discharge stroke relative to the pump body 1 and plunger 30 rotatable therein when the engine

compression pressure applied to the piston is sufficient to overcome the force of the spring washers 35.

Initial movement of the piston 45 and sleeve 13 on the fuel discharge stroke causes the external flange 15 on the sleeve to move out of the smaller diameter portion 17 of the body counterbore 6 and causes displacement and by-pass of fuel out of the pumping chamber 53 through the passages 75-77 and groove 73 in the rotatable plunger and port 69 in the reciprocal sleeve 13 until this port moves out of register with the groove 73 to trap and compress the fuel in the pumping chamber 53 and into register with the bottom of the bottom edge of the small diameter portion 17 of counterbore 6 in the body to allow fuel supply pressure to enter this counterbore. The inlet and relief port 71 in the sleeve simultaneously moves out of register with the helical groove 78 of the rotatable plunger 29 to trap fuel in this groove. Upon a further and rapid rise in the engine compression pressure the piston 45 and sleeve 13 continue to move inwardly and compress the fuel trapped in the pumping chamber 53 which also opposes this movement along with opposing force of the spring washers 35. The inner edge of the internal groove 55 of the reciprocal sleeve next registers with the helical discharge groove 78 in the rotatable plunger 29 to equalize the pressure therein with that in the pumping chamber 53. This varies the force opposing inward movement of the piston 45 and sleeve 13. After a predetermined travel the discharge port 72 in the reciprocal sleeve 13 then registers with the helical discharge groove 78 of the rotatable plunger to start discharge of the compressed fuel from the pumping chamber 53 through the helical discharge groove 78, discharge port 72 and passages 79-81-83-85 and 89 in the sleeve 13 and plunger 29, valve seat 41 and nozzle 43 and directly into the engine combustion chamber causing fuel injection and combustion of fuel in the engine combustion chamber. The land 59 in the bore of the sleeve 13 next moves over the end of the rotatable plunger 29 preventing any further compression of the fuel in the internal groove portion 55 of the pumping chamber inside the land 59 and thereby stops further discharge and injection therefrom and to retrap and further compress the fuel in the outer internal groove portion 57 of the chamber and thereby provide a hydraulic lock between the plunger and sleeve to stop further movement of the piston 45 and sleeve. The flange 15 of the sleeve is in the inner end counterbore of the flanged closure member 21 which is supplied with fuel at supply pressure through the body counterbore 6, as described above, to provide an additional hydraulic lock to also stop movement of the piston and sleeve on the discharge stroke to prevent metal to metal contact between this flange 15 and closure member 21.

It will be evident that varying the longitudinal spacing of the grooves 73-78 of the rotatable plunger 29 or the width thereof causes different compression and pressure of fuel trapped in the pumping chamber prior to the start of injection. With the spacing and width of these grooves determined, angular adjustment of the rotatable plunger helical discharge groove 78 varies the start of injection relative to the end of injection which is determined by the movement of the sleeve land 59 past the inner end face of the rotatable plunger 29 to determine the end of the

effective discharge or injection stroke of the fuel injection pump and the amount of fuel injected during this time. The relative longitudinal displacement of the internal grooves 55—57 and the land 59 therebetween of the reciprocal sleeve 13 and their widths may be changed to vary the end of injection and control the compression of fuel and pressure in the pumping chamber or portions thereof to suit different compression pressure values for different engines.

The modified fuel injection pump structure shown in Figure 3 also includes a relatively movable plunger and sleeve of similar form to that previously described. This pump includes a pump body 101 having an axial bore 102, a sleeve 105 having an external flange 106 seated on one end face of the body by a check valve seat member 107 which is seated on the outer end of the sleeve by a fuel nozzle 108 in seating engagement therewith and having an external flange 109 which is engaged by an internal flange of a hollow cap member 110 threaded on the fuel pump body 101. A plunger 111 is reciprocal in the sleeve 105 and the space in the sleeve between the inner end of the plunger and the check valve seat serves as a fuel pumping chamber, which is generally indicated at 113. It will be noted that the sleeve 105 is provided with an internal groove 115 forming the inner wall portion of the pumping chamber adjacent the outer end of the sleeve bore closed by the check valve seat member 107. The cap 110 is provided with an external conical seating surface 117 which is seated on a similar complementary seating surface in an opening of an engine cylinder head, not shown, and communicating with the engine combustion chamber; suitable hold-down means being provided on the cylinder head, similar to that indicated generally at 28 in Figure 1, to hold the cap 110 seated in the cylinder head opening.

The plunger 111 is provided with an external flange 118 at the outer end shown positioned between an internal flange of a hollow follower guide 119, slideable in the outer end of the body bore 103, and a follower 121 held in the hollow guide by a pin 123. The hollow guide 119 is provided with a longitudinal slot 125 in which the inner end of a pin 127 secured in an extension of the body 101 projects, to prevent rotation of the follower 121 and guide 119. A helical compression spring 129 is placed between the body 101 and an external flange 131 of the guide 119 and normally urges the guide, follower and plunger outwardly of the body and sleeve on the fuel filling stroke to the position shown in Figure 3 so that the pin 127 in the body contacts the inner end of the guide slot 125. Movement of the plunger 111 inwardly of the body and sleeve on the fuel discharge stroke is accomplished by a suitable engine operated rocker lever 133 having a roller 135 thereon in engagement with the follower 121.

The plunger 111 is provided with a hexagonal portion 137 adjacent the outer end which is slideable in an internal hexagonal portion of a pinion 139 located between a hollow spacer 141 in the inner end of a counterbore of the body and in contact with the outer end of the sleeve 105 and a thrust washer 143 in the outer end of the body counterbore. A rack 145 is reciprocal in a transverse bore in the body and meshes with the pinion for rotating it and the plunger 111 relative to the sleeve 105.

The body 101, cap 110, sleeve 105 and plunger 111 are provided with the following fuel passages,

5 ports and control edges which are similar to those previously described in the injection pump shown in Figures 1 and 2. A fuel pressure supply passage comprising radial and longitudinal communicating drilled passages 147—149, the latter opening into the space 151 between the cap 110 and sleeve 105. The sleeve 105 is provided with a combined fuel inlet and by-pass port 153 opening into the space 151 and a drilled passage extending diametrically part way through the sleeve forms a combined inlet and relief port 155 opening into the space 151 and a discharge port 157 diametrically opposite the port 155. A longitudinal discharge passage 159 in the sleeve 105 leads from the discharge port 155 to registering annular grooves 161 in the seated surfaces of the sleeve and check valve seat. A discharge passage 163 extends from the annular grooves 161 to the center of the outer face of the check valve seat 107 and opens into a counterbored portion 165 of an axial bore 167 in the fuel nozzle 108. Fuel spray openings 169 are provided in the top of the nozzle and these openings extend radially and angularly outwardly from the axial bore 167. A valve disk 171 is located in the counterbored portion 165 of the fuel nozzle and is provided with peripheral grooves by which fuel is discharged past the disk when it is spaced from the center opening in the valve seat member 107.

20 The plunger 111 is provided with a combined fuel inlet, by-pass and relief groove 173 of semi-circular form and radial and axial passages 175—177 leading therefrom to the pumping chamber 113. The plunger groove 173 registers with the combined inlet and by-pass port 153 of the sleeve 105 when the plunger is at the end of the fuel filling stroke to cause filling of the pumping chamber and the above passages with fuel. With the plunger in this position it will be noted that a helical discharge groove 179 provided thereon registers with the combined inlet and relief port 155 of the sleeve to likewise cause fuel filling of this groove.

25 Initial inward movement of the plunger 111 by the rock lever 133 against the force of the spring 129 causes fuel in the pumping chamber 113 to be by-passed outwardly therefrom through the plunger passages 175—177, plunger groove 173 and sleeve inlet and by-pass port 153 until this groove moves out of register with this port and traps fuel in the pumping chamber. The helical plunger groove 179 also moves out of register with the inlet and relief port 155 of the sleeve 105 at this time and traps fuel in the helical groove. 30 Further inward movement of the plunger 111 causes compression and pressure increase of the fuel trapped in the pumping chamber. The helical plunger groove 179 then registers with the internal groove 115 of the sleeve and equalizes the pressure therein with that of the trapped and compressed fuel in the pumping chamber after which the helical groove 179 registers with the discharge port 157 to start discharge of the compressed fuel through this groove and port from the pumping chamber 113 to and through the passages 159, 181, 183, 185, 187 in the sleeve 105, seat member 107 and nozzle 108 and outwardly through the fuel spray openings 169 in the nozzle tip into the engine combustion chamber. Discharge of fuel continues until the plunger inlet and relief groove 173 registers momentarily with the sleeve inlet and relief port to relieve the pressure in the pumping chamber and passages 175—177 momentarily as the inner end 35 surface of the plunger 111 immediately there-

after moves past the sleeve groove 115 and stops further release of pressure from this inner groove portion of the pumping chamber 113 and to end fuel discharge therefrom, however, relief of pressure from the outer or end bore portion of the pumping chamber continues to relieve the mechanical load on the engine driven rocker lever 133.

It will be evident that the mechanically operated fuel injection pump, shown in Figure 3, has similar structural details to that of the compression pressure operated pump, shown in Figures 1 and 2. The compression and pressure of fuel trapped in the compression chamber 113 of the pump shown in Figure 3 is determined by the amount of plunger movement after the plunger grooves 173-178 move past the sleeve ports 153-158 until the plunger discharge port registers with the sleeve discharge port 151 which causes the start of discharge and injection of fuel into the engine combustion chamber. As previously mentioned the width of the plunger grooves 173-178 and longitudinal spacing and also the angular adjustment of the plunger by the rack 145 and pinion 139 varies the amount of fuel compression and pressure prior to the start of injection relative to end injection which is determined by momentary relief of pressure in the pumping chamber immediately followed by movement of the end of the plunger past the internal groove 115 forming the inner wall portion of the pumping chamber. The mechanically operated injection pump then relieves the pressure in the last part of the discharge stroke to relieve the load on the rocker lever 133 actuating the plunger on the discharge stroke. When the plunger is returned on the filling stroke the compression space 113 is filled by entrance of fuel from the space 151 through registration of the combined inlet and discharge sleeve port 153 and the combined inlet and relief plunger groove 173 and connecting passages 175-177 at the start of the filling stroke and also near the end of the filling stroke by registration of the combined inlet and by-pass sleeve port 153 and the plunger inlet and relief groove 173 and connecting passages 175-177.

We claim:

1. In a fuel injection pump, a sleeve closed at one end and having an internal groove adjacent the closed end, a pair of fuel supply ports and a fuel discharge port, a plunger in the sleeve having a pair of grooves normally registering with the sleeve supply ports, one groove serving as a discharge groove, and a passage from the other groove leading to the inner end of the plunger which is normally positioned adjacent the internal groove of the sleeve and forming part of a fuel pumping chamber wall between the inner end of the plunger and the closed end of the sleeve to cause fuel filling of these plunger grooves and passages and the pumping chamber, and means for causing relative movement between the sleeve and plunger to initially cause closure of the sleeve supply ports by the plunger to trap and compress the fuel in the pumping chamber, to next cause registration of the sleeve discharge port and internal groove with the plunger discharge groove and thereby cause discharge of the compressed fuel and to then cause alignment between the internal sleeve groove and inner end of the plunger to end fuel discharge from the chamber.

2. In a fuel injection pump, a sleeve closed at

5 one end and having an internal groove adjacent the closed end, a pair of fuel supply ports and a fuel discharge port, a plunger in the sleeve having a pair of grooves, one groove normally registering with a sleeve supply port and a passage in the plunger leading therefrom to the inner end of the plunger which is normally positioned adjacent the internal sleeve groove forming part of a fuel pumping chamber between the inner end of the plunger and closed end of the sleeve, the other plunger groove being of helical form and normally registering with the other sleeve supply port so that the plunger grooves and passages and the pumping chamber are filled with fuel, means for causing relative axial movement between the plunger and sleeve to initially cause trapping and compression of the fuel in the pumping chamber and plunger passages leading thereto by closure of the sleeve supply ports by the plunger, to then cause the helical plunger groove to register with the internal sleeve groove and discharge port to cause the start of discharge of the compressed fuel and to then cause alignment of the internal sleeve groove with the inner end of the plunger to end fuel discharge and means for causing relative angular motion between the sleeve and plunger to vary the start of fuel discharge.

3. In a fuel injection pump, a sleeve closed at 30 one end and having an internal groove adjacent the closed end, a fuel supply and by-pass port, and a pair of ports in the same plane between the fuel supply and by-pass port and internal groove, one port of this pair of ports serving as a supply port and the other port of this pair of ports serving as a discharge port, a plunger in the sleeve having a groove normally registering with the supply port and passages leading therefrom to the inner end of the plunger which is 35 normally positioned adjacent the internal sleeve groove which forms part of the fuel pumping chamber between the inner end of the plunger and closed end of the sleeve to fill this plunger groove and passage and also the chamber with 40 fuel, the plunger also having a helical discharge groove normally registering with the other supply port in the plane of the discharge port to fill this groove, means causing relative axial movement between the sleeve and plunger to first cause 45 closure of the sleeve supply ports by the plunger to cause trapping and compression of the fuel in the pumping chamber and plunger grooves and passage, to next cause registration of the sleeve discharge port and internal groove with the helical plunger discharge groove to cause the start 50 of discharge of the compressed fuel from the chamber and finally to cause alignment of the inner end of the plunger with the internal sleeve groove to end discharge of fuel from the chamber and means causing relative angular movement 55 between the sleeve and plunger to vary the start of discharge of the compressed fuel from the pumping chamber.

4. In a fuel injection pump, a sleeve closed at 60 one end and having an internal groove adjacent the closed end, a fuel supply port and a pair of diametral ports between the supply port and internal groove, one port of this diametral pair serving as a second supply port and the other 65 serving as a discharge port, a plunger in the sleeve having a transverse supply groove, a passage leading therefrom to the inner end of the plunger and a helical discharge groove, means causing relative axial movement between the 70 sleeve and plunger to cause registration of each

of the sleeve supply ports with a respective plunger groove and positioning the inner end of the plunger adjacent the internal sleeve groove so that this groove serves as part of a pumping chamber between the inner end of the plunger and closed end of the sleeve, a second means causing opposite relative axial movement between the sleeve and plunger to initially cause closure of the sleeve supply ports by the plunger to trap and compress the fuel in the plunger grooves and passage and in the pumping chamber, to next cause registration of the helical discharge plunger groove with the internal groove and discharge port of the sleeve to control the start of discharge of the compressed fuel and to finally cause alignment between the inner end of the plunger and internal groove to the sleeve to control the end of fuel discharge, and a third means causing relative angular movement between the plunger and sleeve to vary the start relative to the end of fuel discharge.

5. In a fuel injection pump, a pump body having a bore and fuel pressure supply passage opening therein, a sleeve in said bore having a closed end and an internal groove adjacent the closed end, two axially spaced ports in continuous register with the cylinder supply passage, a discharge port in the plane of one of the axially spaced ports, and a discharge passage leading therefrom, a plunger in the sleeve and having two grooves and a passage leading from one to the inner end face, said other plunger groove having a helical control edge, means normally positioning the sleeve and plunger so that the communicating plunger passage and groove are in communication with one of the sleeve ports in communication with the cylinder fuel pressure supply passage to fill the space including the internal sleeve groove between the inner end face of the plunger and closed end of the sleeve and so that the other plunger groove is in communication with the other sleeve port in communication with the cylinder fuel supply passage in order to fill these plunger passages and the space between the plunger and sleeve with fuel, means for causing relative axial movement of the plunger and sleeve from the normal position to first cause closure of the sleeve supply ports by the plunger to trap and compress the fuel in the above plunger passages and the space between the plunger and sleeve, to next establish communication between the internal groove and discharge port of said sleeve with the helical edge of the other plunger groove to control the start of fuel discharge of the compressed fuel from the helical plunger groove and space between the plunger and sleeve through the sleeve discharge port and to finally cause overlapping of the internal sleeve groove and inner end of the plunger to cut off fuel discharge, and a second means for causing relative angular movement between the plunger and sleeve to vary the start of fuel discharge.

6. In a fuel injection pump, a sleeve closed at one end having an internal groove adjacent the closed end serving as a fuel pumping chamber, three separate ports and a discharge passage leading from one port serving as a discharge port, said other two ports being in continuous communication with a source of fuel, a plunger in the sleeve having two grooves and a passage leading from one groove to the inner end face and pumping chamber, the other plunger groove serving as a discharge groove, means resiliently urging the plunger outwardly of the chamber to

cause closure of the sleeve discharge port and registration of the plunger grooves with the other sleeve ports to fill the chamber with fuel, and means for moving the plunger toward and into the chamber, to initially trap and compress the fuel in the chamber by closure of the two sleeve ports in communication with the fuel source by the plunger, to next cause registration of the internal groove and discharge port of the sleeve with the plunger discharge groove to start discharge of the compressed fuel and to then cause momentary registration of the groove having the passage leading to the chamber with the other port in communication with the fuel source to momentarily relieve the pressure therein and immediately thereafter to finally cause closure of the internal sleeve groove by the inner end surface of the plunger to cut off fuel discharge from the chamber.

7. In a fuel injection pump, a sleeve closed at one end and having an internal groove adjacent the closed end, a fuel inlet port and circumferentially spaced relief and discharge ports axially spaced from the inlet port, said inlet and relief ports being in continuous communication with a source of fuel pressure, a plunger in the sleeve to form a pumping chamber including the internal sleeve groove between the closed end of the sleeve and the inner end of the plunger, said plunger having a transverse inlet groove and passage leading therefrom to the inner end face and a helical discharge groove, means normally causing relative movement of the sleeve and plunger to cause closure of the discharge port and to cause each of said other ports to register with one of said plunger grooves to cause fuel filling of said chamber, another means for causing relative movement between the sleeve and plunger to initially cut off fuel filling and trap and compress the fuel in the chamber, to next cause registration of the helical plunger discharge groove with the internal groove and discharge port of the sleeve to start discharge of the compressed fuel from the chamber and finally cause registration of the transverse plunger inlet groove and a sleeve relief port and registration of the inner end of the plunger with the internal groove to stop discharge of fuel from the chamber and means for rotating the plunger in the sleeve to vary the start of fuel discharge.

8. In a fuel injection pump, a pump body having a bore and a fuel pressure supply passage leading thereto, a sleeve in said bore and having a closed end, an internal groove adjacent the closed end serving as a fuel pumping chamber, three separate ports and a discharge passage through the closed end and communicating with one port serving as a fuel discharge port, means for securing the sleeve to the body so that the other two sleeve ports therein are in communication with the pressure supply passage of the body, a plunger having two grooves, one serving as a discharge groove and the other communicating with a passage extending to the inner end face and the pumping chamber, resilient means normally urging the plunger outwardly of the chamber to a fuel filling position to close the sleeve discharge port and passage and cause each plunger groove to register with one of the other two ports, and means for moving the plunger into the chamber to close all three sleeve ports and trap and compress the fuel in the chamber and plunger grooves and passages and then cause the plunger discharge groove to register with the sleeve discharge port and passage and also with the in-

ternal groove of the chamber to start discharge of the compressed fuel and to then cause the other plunger groove and passage to momentarily register with the other sleeve port in communicating with the fuel supply passage and immediately thereafter to cause the internal sleeve groove to be covered by the inner end surface of the plunger thereby momentarily relieving the pressure in the chamber immediately before cut off discharge from the chamber.

9. In a fuel injection pump, a pump body having a fuel supply passage, a sleeve having a closed end slidable in the body and including a pair of ports in continuous register with the body fuel supply passage, a fuel discharge port and an internal groove adjacent the closed end, a plunger on said body and extending into the sleeve and having a pair of grooves one serving as a discharge groove and passages leading from the other groove to the inner end and the space adjacent the closed end of the sleeve including the internal groove, which space serves as a fuel pumping chamber, means normally positioning the sleeve relative to the body and plunger to cause registration of the sleeve supply ports and plunger grooves to cause filling of the pumping chamber with fuel and for also opposing inward movement of the sleeve from this normal position relative to the body and plunger by application of pressure on the outer closed end to initially trap and compress the fuel in the pumping chamber, to next cause registration of the discharge port and internal groove of the sleeve with the plunger discharge groove whereby the compressed fuel is discharged from the pumping chamber through the discharge port and to finally cause alignment of the internal sleeve groove with the inner end of the plunger to end discharge from the pumping chamber.

10. In a fuel injection pump, a pump body having a fuel pressure supply passage, a sleeve closed at one end and slidable in the body and including an internal groove adjacent the closed end, a pair of axially spaced supply ports in continuous register with the body supply passage and a discharge port and discharge passages leading outwardly therefrom through the closed end, a plunger in the body and extending into the sleeve and including a pair of grooves, one serving as a discharge groove and passages leading from the other groove to the end face and space serving as a pumping chamber including the internal groove in the sleeve, means normally positioning the sleeve relative to the body and plunger and to cause registration of the sleeve supply ports with the plunger grooves to fill the pumping chamber with fuel pressure and to resiliently oppose inward movement of the sleeve relative to the body and plunger upon pressure application on the closed end to close the sleeve supply ports and trap and compress the fuel in the pumping chamber, to then cause registration of the internal sleeve groove and discharge port with the plunger discharge groove to start discharge of the compressed fuel from the pumping chamber and to finally cause registration of the internal sleeve groove with the inner end of the plunger to end fuel discharge, retrap and compress fuel in the pumping chamber and thereby stop further inward movement of the sleeve.

11. In a fuel injection pump, a pump body having a fuel pressure supply passage, a sleeve reciprocal in the body and closed at one end to serve as a piston and including an internal groove adjacent the piston, a pair of fuel pressure supply

ports spaced axially apart and in continuous register with the body supply passage and a fuel discharge port in the plane of one supply port and discharge passages leading outwardly from the discharge port through the piston, a plunger rotatably supported in the body and in the sleeve and including a pair of grooves, one groove having a helical edge and serving as a fuel discharge groove and passages leading from the other groove to the inner end face and space in the sleeve including the internal groove and serving as a fuel pumping chamber, means including a spring for normally positioning the sleeve relative to the body and plunger to cause registration of the sleeve supply ports and plunger grooves to fill these grooves and the pumping chamber with fuel under pressure, and for resiliently opposing inward movement of the sleeve by pressure application on the piston to trap and compress the fuel in the pumping chamber, to next cause registration of the internal groove and discharge port and passages of the sleeve with the helical edge of the discharge groove of the plunger to start discharge of the compressed fuel from the pumping chamber and to finally cause alignment of the internal sleeve groove with the inner end of the plunger to end discharge and to retrap and compress fuel in the pumping chamber and thereby limit further inward movement of the sleeve by the piston.

12. In a fuel injection pump, a pump body having a bore, a fuel pressure inlet passage opening into the bore and counterbored end portions, a sleeve reciprocal in the body bore having an enlarged closed end piston portion slidable in one end counterbore of the body, the sleeve having axially spaced supply ports in continuous communication with the body supply passage, a discharge port and passages leading therefrom outwardly of the piston portion and an external flange slidable in the other end body counterbore, a plunger rotatable on the body and in the sleeve and including axially spaced grooves, one groove having a helical edge and serving as a discharge groove and the other having passages leading therefrom to the inner end face of the plunger and space in the sleeve including the internal groove and serving as a fuel pumping chamber, spring means for urging the sleeve and piston outwardly of the body and positioning the sleeve flange in the inner end of the body counterbore and the supply ports in register with the plunger grooves to fill the pumping chamber, the spring means opposing inward movement of the sleeve by pressure application on the piston to initially trap and compress the fuel in the pumping chamber and to cause one supply port to register with the body counterbore below the sleeve flange to next cause the internal sleeve groove, discharge port and passages of the sleeve to register with the helical edge of the plunger discharge groove to start discharge of compressed fuel from the pumping chamber and to finally cause the internal groove to register with the inner end of the plunger to end discharge of fuel from and retrap and compress the fuel remaining in the pumping chamber to stop further inward movement of the sleeve and plunger, said spring returning the sleeve and piston and flange on the sleeve to the normal filling position causing trapping of fuel between the flange and body counterbore thereby preventing contact therebetween.

13. In a fuel injection pump, a pump body having a bore and a fuel pressure supply passage opening therein, a sleeve in said bore and having

a closed end, an internal groove adjacent the closed end serving as part of a fuel pumping chamber, three separate ports and a discharge passage extending through the closed end to one port serving as a fuel discharge port, means securing the sleeve in the body bore so that the other two sleeve ports are placed in communication with the pressure supply passage of the body to serve as fuel supply ports, a plunger in the sleeve having two grooves, one serving as a discharge groove and the other communicating with a passage extending to the end face and pumping chamber, resilient means normally urging the plunger outwardly of the chamber to cause registration of the sleeve supply ports with the plunger grooves to cause fuel filling of the ports, grooves and chamber, and means for moving the plunger into the chamber to close the fuel supply ports and trap and compress fuel in the chamber and piston grooves and passages to then cause the plunger discharge groove to register with the sleeve discharge port and internal groove to start discharge of fuel through the discharge passage and to then cause the other plunger groove to register with one of the sleeve supply ports and reduce the pressure in the pumping chamber, followed immediately thereafter by closure of the internal sleeve groove by the plunger to discontinue fuel discharge and maintain continuous relief of pressure from the pumping chamber.

14. In a fuel injection pump, a pump body having a bore provided with counterbored end portions and a fuel pressure supply opening in the bore, a sleeve reciprocal in the body bore having a closed end piston portion slidable in one end body counterbore, an internal groove adjacent the closed end piston portion and a flange on the other end movable in the other end body counterbore, a sleeve retainer in the open end of the body counterbore in which the sleeve flange is movable, the sleeve also having axially spaced fuel supply ports in continuous communication with the body fuel pressure supply opening, a fuel pressure discharge port and a discharge passage leading therefrom through the piston portion of the sleeve, a plunger rotatably supported in the body and extending into the open end of the sleeve and having axially spaced grooves,

one groove having a helical edge and serving as a plunger discharge groove and a fuel filling passage leading from the other groove to the inner end of the plunger to the pumping space adjacent the sleeve piston portion, spring means urging the sleeve and piston outwardly of the body to position the sleeve flange in the inner end of the body counterbore and the supply ports in register with the plunger grooves to fill the pumping chamber with fuel, the spring opposing inward movement of the sleeve by pressure application to the sleeve piston portion to initially trap and compress the fuel in the pumping chamber and to cause one sleeve supply port to register with the body counterbore and fill it with fuel, to then cause the sleeve discharge port and internal groove to register with the plunger discharge groove to cause discharge of fuel at high pressure outwardly from the pumping chamber through the discharge passage in the sleeve piston portion, to finally cause the internal sleeve groove to be covered by the inner end of the plunger to end fuel discharge and retrap and compress fuel in the pumping chamber to stop further movement of the sleeve, the sleeve flange at this time traps fuel between it and the sleeve retainer to prevent contact therebetween, the spring means in returning the sleeve to the fuel filling position causing the sleeve flange to trap fuel between it and the inner end of the body counterbore to also prevent contact therebetween.

Certificate of Correction

Patent No. 2,576,451

November 27, 1951

JOHN DICKSON ET AL.

It is hereby certified that error appears in the printed specification of the above numbered patent requiring correction as follows:

Column 3, line 5, for "slot 41" read *slot 51*; column 6, line 22, for "the top" read *the tip*; column 14, list of references cited, under "FOREIGN PATENTS" for "Great Britain" read *Germany*; and that the said Letters Patent should be read as corrected above, so that the same may conform to the record of the case in the Patent Office.

Signed and sealed this 18th day of March, A. D. 1952.

[SEAL]

THOMAS F. MURPHY,
Assistant Commissioner of Patents.
